(57) **CLAIM**

The ornamental design for an interflow waterslide, as shown and described.

DESCRIPTION

FIG. 1 is a perspective view of an interflow waterslide showing our new design;

FIG. 2 is a top view thereof;

FIG. 3 is a right side view thereof;

FIG. 4 is a front view thereof;

FIG. 5 is a perspective view showing the interflow waterslide in an alternate configuration with only the triangular center shown for clarification;

FIG. 6 is another perspective view thereof;

FIG. 7 is a top view thereof;

FIG. 8 is a front view thereof;

FIG. 9 is a rear view thereof; and,

FIG. 10 is a right side view thereof, a left side view being a mirror image of the right side view.

1 Claim, 10 Drawing Sheets
